WALL MOUNTED PRINTING TELEGRAPH APPARATUS CABINET

Walter J. Zenner, Des Plaines, Ill., assignor to Teletype Corporation, Skokie, Ill., a corporation of Delaware

Filed Dec. 6, 1961, Ser. No. 67,823

Term of patent 14 years

(Cl. D64—11)

FIG. 1

FIG. 2

FIG. 1 is a front perspective view of a wall mounted printing telegraph apparatus cabinet showing my new design; and

FIG. 2 is another front perspective view thereof showing the side of the cabinet opposite to that of FIG. 1.

The back of the cabinet is plain and un-ornamented. I claim:

I claim:

The ornamental design for a wall mounted printing telegraph apparatus cabinet, substantially as shown and described.
